[57] CLAIM

The ornamental design for a bicycle accessory light fixture, as shown and described.

DESCRIPTION

FIG. 1 is a perspective view of a bicycle accessory light fixture showing my new design;

FIG. 2 is a side-elevational view of the side not seen in FIG. 1 on an enlarged scale;

FIG. 3 is a rear-elevational view thereof on an enlarged scale; and

FIG. 4 is a bottom-plan view thereof on an enlarged scale.

FIG. 4
